UNITED STATES PATENT OFFICE

DANIEL TOWNEND, OF PROVIDENCE, AND NELSON C. WHITE, OF CRANSTON, RHODE ISLAND, ASSIGNORS TO FIELDS POINT MANUFACTURING CORPORATION, OF NEW YORK, N. Y., A CORPORATION OF RHODE ISLAND

CHEMICAL MANUFACTURE

Application filed July 30, 1931. Serial No. 553,994.

This invention relates to improvements in electrolytic cells of the diaphragm type such as are commonly used in the electrolysis of sodium chloride brines for the production of chlorine and caustic soda liquor. This type of electrolytic cell comprises, generally, a cell chamber, a cathode member arranged within the cell chamber, an anode member arranged within the cathode member, a diaphragm arranged between the anode member and the cathode member, and a cell cover shaped to form a chamber for collection of the gas produced by the electrolysis. The anode member is usually of carbon and the diaphragm is usually either of paper or cloth or composite paper-cloth construction. Replacement of the anode member and of the diaphragm, commonly designated "rebuilding" of the cell, is a regularly occurring part of the operation of such electrolytic cells. From the standpoint of economy of operation, the cells must be arranged to facilitate such "rebuilding"; that is the cells must afford a maximum of accessibility. At the same time, gas leakage must be reduced to a minimum. These two factors are not entirely consistent since the provision of means for ready access to the cell interior usually involves multiplication of joints subject to gas leakage or related difficulties. This invention provides an improved electrolytic cell of this type affording a number of important advantages with respect to accessibility while eliminating joints subject to gas leakage.

The improved electrolytic cell of the present invention comprises a cell chamber open at the top, a cathode member arranged within the cell chamber having a portion extending outwardly across the upper edge of the cell chamber, this outwardly extending portion being formed to provide on its upper side a sealing tongue, a cell cover provided with a sealing groove fitting the sealing tongue on the outwardly extending portion of the cathode member, an anode member arranged within the cathode member and a diaphragm arranged between the anode member and the cathode member, the tip of the sealing tongue on the upper side of the cathode member extending above the normal liquid level in the

cell and the inner lip of the sealing groove in the cover extending below the normal liquid level in the cell. The joint between the cathode member and the cell cover, is thus, in effect, rendered self-sealing. Immediate access to the diaphragm can be had by the simple expedient of lifting the cell cover from the cathode member while the equally simple replacement of the cell cover on the cathode member re-establishes the seal between these two elements. The anode member is advantageously arranged to be supported by the cell cover, so that the sealing cover and anode member assembly can be removed by a single simple operation. Advantageously, the cell chamber is provided with a sealing tongue around its upper edge and the outwardly extending portion of the cathode member is formed to provide on its lower side a sealing groove fitting the sealing tongue on the upper edge of the cell chamber. This additional seal is included in the more specific aspects of the invention.

The invention will be further described in connection with the accompanying drawings which illustrate, diagrammatically and conventionally, one form of electrolytic cell embodying the invention. In the accompanying drawings, Fig. 1 is an elevation, partly in section and with parts broken away, of a cell embodying the invention, Fig. 2 is a section on line 2-2 in Fig. 1, Fig. 3 is an enlarged detail, in section, of the joint between the cell chamber and the cell cover, and Figs. 4 and 5 are enlarged details of arrangements for sealing the joints between the gas off-take pipe and the cell cover and between the cover and extensions of the anode member therethrough.

The electrolytic cell illustrated comprises a cell chamber 6 open at the top and provided with a sealing tongue 7 around its upper edge, a cathode member 8 having a portion 9 extending outwardly across the upper edge of the chamber 6, this outwardly extending portion being formed, as illustrated at 10, to provide on its lower side a sealing groove fitting the sealing tongue 7 and on its upper side a second sealing tongue, a cell cover 11 provided with a second sealing

groove 12 fitting the second sealing tongue on the outwardly extending portion 9 of the cathode member 8, a plurality of anode members 13 arranged within the cathode member 8, and a diaphragm 14 arranged between the anode member 13 and the cathode member 8. The sealing tongue 7 and the co-operating sealing groove in the lower side of the outwardly extending portion 9 of the cathode member are advantageous but are not essential in the broader aspects of the invention. The normal liquid level in the cell is indicated at 15. The normal liquid level falls between the upper edge, or tip, of the sealing tongue on the outwardly extending portion 9 of the cathode member and the lower edge of the inner lip of the sealing groove 12 in the cover member 11. As in the cell illustrated, the anode members 13 are advantageously arranged to be supported solely by the cover member 11, so that the cover member and the anode member assembly may be removed and replaced as a unit. The anode members 13, in the cell illustrated, are supported by bus bars 16 which in turn are supported by projection 17 on the cover member.

In the cell illustrated the cathode member is supported from the upper edge of the cell 30 chamber 6 by the outwardly extending portion 9 of the cathode member, and the diaphragm 14 is supported by the cathode member 8. It will be apparent that removal of of the cover member and the anode members affords an immediate and complete access to the diaphragm. In the cell illustrated, each of the extensions 18 of the anode members 13 is provided with a skirt 19 extending downwardly into a lute 20 filled with oil or some appropriate putty or cement 40 resistant to the action of the gas or gas mixture produced in the cell. The gas off-take pipe 21 is similarly provided with a skirt 22 extending downwardly into a lute 23 filled with an appropriate sealing medium. Connection 24 is provided for supplying brine, or other solution to be subjected to electrolysis, to the cell. The outwardly extending portions 9 of the cathode member 8 are connected to bus bars 25. Connection 26 is provided for the discharge of the electrolyzed solution.

In the electrolysis of sodium chloride brines for the production of chlorine and 55 caustic soda liquor, for example, in the form of electrolytic cell illustrated in the drawings, sodium chloride brine is supplied to the space between the diaphragm and the anode members through connection 24, chlorine formed is collected in the chamber provided 60 in the cell cover and discharged through pipe 21, hydrogen formed is collected in and discharged from the space between the cathode member and the cell chamber, and caustic soda liquor formed at the cathode member

by percolation of the brine through the diaphragm is discharged through connection 26. The space between the cathode member and the cell chamber is normally filled with gas, a liquid level sufficient merely to effect discharge of the caustic soda liquor through the connection 26 being maintained beneath the lower part of the cathode member. 70

The cell chamber, the cathode member, the diaphragm, and the anode member may be constructed of any of the conventional materials. The cell cover may be constructed of concrete or hard rubber, for use in the electrolysis of brine for the production of chlorine and caustic soda for example, or of other material resistant to the gas or gas mixture produced in the cell. The cell cover is advantageously constructed in but a single piece, as a unitary casting for example. The skirts 19 and 22 may, for example, be constructed of steel covered with vulcanized rubber, for use in the electrolysis of brine for the production of chlorine and caustic soda, or of other material resistant to the gas or gas mixture produced in the cell. 80

It will be apparent from the foregoing description that the improved electrolytic cell of this invention combines a maximum of accessibility with a minimum of joints subject to gas leakage. The particular joints between the cathode member and the cell cover and between the cell chamber and the cathode member provided by this invention have the further advantage of being unusually rugged. They are not easily damaged and can be opened and closed an indefinite number of times. 95

We claim:

1. An electrolytic cell comprising a cell chamber open at the top, a cathode member arranged within said chamber having a portion extending outwardly across the upper edge of said chamber, said outwardly extending portion being formed to provide on its upper side a sealing tongue, a cell cover provided with a sealing groove fitting said sealing tongue, an anode member arranged within said cathode member and a diaphragm arranged between said anode member and said cathode member, the tip of said sealing tongue extending above the normal liquid level in the cell and the inner lip of said sealing groove extending below the normal liquid level in the cell. 110

2. An electrolytic cell comprising a cell chamber open at the top, a cathode member arranged within said chamber having a portion extending outwardly across the upper edge of said chamber, said outwardly extending portion being formed to provide on its upper side a sealing tongue, a cell cover provided with a sealing groove fitting said sealing tongue, an anode member arranged within said cathode member and supported solely by said cover, and a diaphragm arranged be- 125

tween said anode member and said cathode member, the tip of said sealing tongue extending above the normal liquid level in the cell and the inner lip of said sealing groove extending below the normal liquid level in the cell.

3. An electrolytic cell comprising a cell chamber open at the top and provided with a sealing tongue around its upper edge, a cathode member arranged within said chamber having a portion extending outwardly across the upper edge of said chamber, said outwardly extending portion being formed to provide on its lower side a sealing groove fitting said sealing tongue and on its upper side a second sealing tongue, a cell cover provided with a second sealing groove fitting said second sealing tongue, an anode member arranged within said cathode member and a diaphragm arranged between said anode member and said cathode member, the tip of said second sealing tongue extending above the normal liquid level in the cell and the inner lip of said second sealing groove extending below the normal liquid level in the cell.

4. An electrolytic cell comprising a cell chamber open at the top and provided with a sealing tongue around its upper edge, a cathode member arranged within said chamber having a portion extending outwardly across the upper edge of said chamber, said outwardly extending portion being formed to provide on its lower side a sealing groove fitting said sealing tongue and on its upper side a second sealing tongue, a cell cover provided with a second sealing groove fitting said second sealing tongue, an anode member arranged within said cathode member and supported solely by said cover, and a diaphragm arranged between said anode member and said cathode member, the tip of said second sealing tongue extending above the normal liquid level in the cell and the inner lip of said second sealing groove extending below the normal liquid level in the cell.

In testimony whereof we affix our signatures.

DANIEL TOWNEND.
NELSON C. WHITE.
